(57) **CLAIM**

The ornamental design for a foot massager, as shown and described.

DESCRIPTION

FIG. 1 is a perspective view of a foot massager showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the foot massager of FIG. 1 when folded; and,

FIG. 10 is an enlarged view of the encircled portion in FIG. 1.

The equal-length broken lines depict portions of the foot massager that form no part of the claimed design.

The dash-dot lines in FIG. 1 and FIG. 10 illustrate the boundaries of the enlarged view indicators and form no part of the claimed design.
